Primary Examiner — Daniel Bui*Assistant Examiner* — Andrew Kerr(74) *Attorney, Agent, or Firm* — Foley & Lardner LLP(57) **CLAIM**

We claim the ornamental design for a cabinet for use with a genset enclosure, as shown and described.

DESCRIPTION

FIG. 1 is a top, front, and left perspective view of a cabinet for use with a genset enclosure showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a rear perspective view thereof.

The bottom of the cabinet for use with a genset enclosure is unornamented and forms no part of the claimed design. Additionally, the hollow interior surface of the cabinet for use with a genset enclosure forms no part of the claimed design.

The ornamental design which is claimed is shown in solid lines in the drawings. The broken lines shown in the drawing views represent unclaimed portions of the cabinet for use with a genset enclosure, and form no part of the claimed design.
